(57) **CLAIM**

The ornamental design for a decorative cover for a dispenser, as shown and described.

DESCRIPTION

FIG. 1 is a top and front perspective view thereof of a decorative cover for a dispenser showing my new design;
FIG. 2 is an additional top and front perspective view thereof, with the broken-line disclosure of a pump being for illustrative purposes only and forming no part of the claimed design;
FIG. 3 is a front elevational view thereof;
FIG. 4 is a rear elevational view thereof;
FIG. 5 is a top plan view thereof;
FIG. 6 is a bottom plan view thereof; and,
FIG. 7 is a vertical cross-sectional view thereof taken through the center of the article.
